UNITED STATES PATENT OFFICE

BURNHAM C. STICKNEY, OF HILLSIDE, NEW JERSEY, ASSIGNOR TO ELLIOTT-FISHER COMPANY, OF NEW YORK, N. Y., A CORPORATION OF DELAWARE

COMBINED TYPEWRITING AND ADDING MACHINE

Application filed August 11, 1922. Serial No. 581,051.

This invention relates to adding machines, especially those which are combined with typewriting machines, and is illustrated in connection with a machine of the Hanson type, or the well-known Underwood book-keeping machine.

In such machines, the typewriting mechanism is positioned above the adding mechanism. The digit-keys of the typewriting mechanism operate indexing devices of the adding mechanism, and, after the typing of a number is completed, a general operator is used for running the number into the dial-wheels of the register. The indexing devices usually consist of a set of pins, and each digit-key is capable of setting a pin in any denomination. The denominations are selected by the typewriter-carriage, one after another, as the carriage progresses. The present improvements relate principally to the denomination-selecting mechanism.

The indexing pins are arranged in denominations and are mounted upon bars, these denominational pin-bars being connected by individual trains to a set of denomination jacks, which are displaced one after another by means of a dog mounted upon the typewriter-carriage. Displacing of the denominational pin-bars bring the pins thereon into position to be set by the digit-keys.

Usually in an Underwood machine having two or more registers, a complete system of denominational trains, including the jacks, is provided for each register. The registers are simultaneously operated, and the carriage must set jacks for all the registers simultaneously, thus putting considerable load on the driving spring which propels the typewriter-carriage. One of the objects of this invention is to reduce this load, and to simplify the means whereby the carriage may set denominational pin-bars simultaneously for a plurality of registers.

To this end, each register is provided with its set of indexable computing bars, and connections are provided from a single set of jacks to set pin-bars in all of the registers simultaneously, each jack being arranged to operate a rock-shaft, these rock-shafts ex-

tending transversely of the machine, and each rock-shaft having arms thereon for displacing all of the pin-bars of the same denomination for the various registers.

In the preferred manner of practicing the invention, all of said pin-bars are normally out of reach of the jack trains or denomination-selecting mechanism, and the pin-bars of each register are brought into co-action with the jack trains by means of an individual cam operable by the typewriter-carriage, this cam being held depressed and the pin-bars accordingly functioning so long as the carriage is traversing the typing zone which is involved. While the carriage is out of said zone, such set of pin-bars is out of co-action with the jack trains.

Two or more sets of pin-bars may be brought simultaneously into use for co-operation with the jack trains by the use of individual cams for each set of pin-bars, so that computation may proceed in several registers simultaneously.

Said cams may be carried upon blocks mounted on the carriage and the same blocks may carry the denominational selecting dogs, previously referred to. There may be provided for each machine a plurality of blocks; each block having one, two or three cams. Thus, the mechanism and operation of setting the machine up for a variety of work is greatly simplified. Said blocks may be formed with column stops, and may be adjustable along a rack for arresting the carriage at the tabulating operation.

The provision of the transverse rock-shafts in the jack trains permits the placing of a register mechanism at the extreme right or the extreme left portion of the machine, while the jacks remain at the middle of the machine, and this is an advantage whether or not additional registers are employed.

As the typewriter-carriage travels from right to left, the denominational selecting dog acts first upon the right-hand jack which must, therefore, be included in the highest denominational train. Since the right-hand wheel in the register is a units wheel, a transposition device is usually em-

ployed between the jacks and the indexing pin-bars.

One of the objects of the invention is to avoid the necessity for using any interposed transposition device, and thereby to save parts and reduce cost, and also conduce to greater ease and certainty of operation. To this end, rods are connected at their lower ends to arms on the transverse rock-shafts 10 of appropriate denominations and extend directly up to the denominational jacks, so that a denominational train comprises only the jack, the rod, the rock-shaft, and the pin-bar.

15 Other features and advantages will hereinafter appear.

In the accompanying drawings,

Figure 1 is a side elevation of a block adjustable on the carriage and carrying a denomination-selecting dog, and also one or more cams for controlling the selection of registers. This block also serves as a column stop for the tabulating operation of the carriage.

20 Figure 2 is a sectional elevation taken at the line 2—2 of Figure 1.

Figure 3 is a sectional elevation taken at about the line 3—3 of Figure 4 of an Underwood bookkeeping machine embodying the 25 present improvements in one form.

Figure 4 is a rear elevation of the machine, showing particularly the denomination-selecting and register-selecting devices.

Figure 5 is a sectional plan of the rear 30 portion of the machine, showing the sets of indexing pin-bars and their relationship to the denominational jack trains.

The typewriting mechanism comprises alphabet type-keys 10 and digit type-keys 40 11, all mounted on levers 12, which, by means of bell-crank 13, drive type-bars 14 up to strike against a platen 15, the latter mounted on a carriage 16 which runs along front and rear guide-rails 17, 18, and is 45 driven by a spring, not shown. For controlling its letter-feeding movements, the carriage has a releasable rack 19, which meshes with a pinion 20, the latter connected to an escapement-wheel 21, which is 50 controlled by dogs 22 and 23. Vibrating movements of the dogs are effected by a curved universal bar 24, which is operated by the type-bars and has a frame portion 55 which engages directly with the dog-rocker.

From each of the digit type-keys 11 depends a stem 27, which, when depressed, engages at its lower end an arm 28 on a rock-shaft 29, there being one rock-shaft for 60 each key 11. These rock-shafts 29 individually operate linkages 30, which are connected to arms 31 on the rock-shafts, and lower links or digit bars 32, which are also connected, through linkages 30, to the arms 65 31 and are depressed thereby for the pur-

pose of depressing indexing pins 33, the latter being carried upon forwardly and rearwardly extending denominational computing elements or pin-bars 34. After a number is typed and its corresponding number pins are set, a general operator 35 is operated, which may be power driven, but is illustrated as operated by a handle 36 connected to a rock-shaft 37, the latter having sectors 38 meshing with idle pinions 39, and the latter meshing with racks 40 forming part of the general operator and having a transverse bar 41, which, as it moves forward, engages the depressed pins 33, and, by means of racks 34^a on the forward ends 70 of the pin-bars, drives the register dials 75 accordingly. The pins 33 are all normally out of the paths of the digit bars 32, but each file of pins may be brought into said paths by displacing forwardly the pin-bar 34 which carries said pins. One of the features of the present improvements relates to the manner of effecting such forward displacement of the pin-bars.

At its rear end, each of the pin-bars 34 90 carries a pin 42, whereby it may be set or displaced forwardly. These pins may be in the paths of arms 43 extending upwardly from a series of horizontal transverse rock-shafts 44, so that, when any shaft is rocked, 95 its arm 43 is rocked and its corresponding pin-bar is displaced forwardly to bring its index pins 33 into the paths of the digit bars or links 32. The rock-shafts 44 are mounted on brackets 44^a fixed to the machine frame, and are normally pulled by springs 44^b in a clockwise direction, as seen in Figure 3, to cause stops 44^c on the shafts to engage with stops 44^d on one of the brackets to thus hold said shafts in their 100 normal positions. Each of the rock-shafts 44 is provided with a controlling arm 45 to which is pivoted the lower end of a rod 46, the rods extending upwardly and being suitably guided in a plate 47 near their 105 upper ends. To depress the rods 46, there is provided a set of jacks 48 pivoted between their ends, the forward ends 49 of the jacks each having a tooth 50, and these teeth being engageable by a dog 51 upon the typewriter-carriage to lift the jacks one after another as the carriage is passing through the computing zone, that is, while typing is being done in the column for which computation is to be effected. These jacks may be 110 all substantially of the usual type, and, as the front end of any jack is lifted, its rear end is depressed, thereby pressing down its rod 46 and rotating the connected rock-shaft 44. By means of these jack trains the pin-bars 34 may be properly advanced or displaced one set after another as the typewriter-carriage proceeds step by step 115 through the computing zone.

Each of the transposing rock-shafts 44 120

carries an arm 43 to drive the corresponding pin-bar 34 in every register set, of which three are illustrated, so that indexing pins may be set simultaneously in all the registers by the use of only one set of jacks or jack trains.

In order to adapt the machine to operate in each single register or only two registers or all three registers at will when typing in any zone, means is provided for disconnecting any one or more sets of pin-bars 34 from the jack trains. Preferably, the connection and disconnection are effected automatically, although the invention is not limited to an automatic operation. To this end, all of the sets of denominational bars may be held normally up with the pins 42 at their rear ends out of reach or range of the arms 43 on the transverse shafts 44 of the jack trains. Separate vertically-movable slides 53, one for each register are provided, and these are held in normally raised positions, with their shoulders 54 in engagement with a positioning stop 55, by coil springs 56 connected to them, respectively, and to a stationary part of the machine frame. The rear slide 53 is pivotally connected at its lower end to one leg of a U-shaped lever 56^a, pivoted on shaft 57, which is supported in stationary brackets 58, 59 on the machine frame. The forward leg 60 of this lever pivotally supports at its middle a yoke 61, having a rectangular opening through which the pin-bars 34 of the middle register pass. In its normally raised position this slide 53 is effective, through the connections described, to hold the pin-bars 34 of the middle register in raised position, with their pins 42 above the path of movement of the arms 43 on the rock-shafts. The other slides 53 are pivoted at their lower ends to separate bell-crank levers 62, which levers are pivoted upon the shaft 57 between the legs of the lever 56^a. These bell-cranks are connected through the links 63 to operate bell-cranks 64 mounted on the machine frame. The respective bell-cranks 64 pivotally support yokes 61 surrounding the pin-bars 34 of the outer registers for normally holding these bars out of the paths of movement of the arms 43. When all of the pin-bars 34 are thus held up by said springs no computation can take place.

Upon the carriage will be provided three cams 65, one for each of the vertical slides 53 to depress it against the tension of the springs 56, thereby lowering the connected yoke 61 and bringing the pin-bars 34 into position to co-act with the jack trains while the carriage is in the computing zone. These cams may all be provided upon a single control block 66 when all of the registers are to be effective simultaneously. Each block 66 carries a denomination-selecting dog 51, previously mentioned. The block 66 has jaws

70, whereby it may be set to any desired columnar position upon the rack 71 provided upon the typewriter for the tabulating mechanism.

Upon the lower part of the block may be 70 formed a column stop 72 to co-operate in the usual manner with the usual denominational stops 73 of the tabulator.

At the upper end of each of the slides 53 is mounted a cam 74, pivoted between its ends to the slide and having a beveled upper face extending above the upper end of the slide. A spring 75, connected to the lower end of the cam 74 and to the slide, normally tends to force the lower end of the cam to its limit of movement in one direction, which limit is determined by engagement with a pin 76 on the slide. When the carriage is entering a computing zone, the beveled faces of the cams 65 upon the control blocks 66 75 strike the beveled top faces of the cams 74, causing them and consequently the slides 53 to be thrust bodily downward. They are held down by the horizontal edges or dwells on the cams 65 until the carriage passes out of the computing zone. Upon the return of the carriage, the vertical end faces of the cams 65 strike against the upper portions of the cams 74, which are swung about their pivots against the pressure of the springs 75 and are restored thereby to normal vertical positions after the cams have passed.

While, as thus described, all three registers may be in use simultaneously in the computing zone of a selected control block 66, the invention may be practiced by omitting any one or any two cams from the control block, so that, while the machine is being operated in the zone controlled by said block, any one or any two registers will be effective. It will thus be seen that there are several possible modes of operation of the three registers in any computing zone, because of the range of selection of control blocks afforded by the different cam arrangements, among these arrangements being, any one of the three cams individually, three possible combinations of two cams, and one combination of all three cams.

There may be provided upon the carriage a series of control blocks 66, as shown in Figure 4. Since the block inserted in any of the positions shown may control the registers in any one of seven different ways, 120 according to the cam or cams upon it, the possible modes of operation of the entire machine will be seven raised to the *n*th power, where "*n*" represents the number of control blocks actually employed. It will, 125 therefore, be seen that the machine is adapted to be set up in any way desired for difficult classes of work by the use of a simple, inexpensive device, readily applied and easily used. The dwell portions of the 130

cams may be of different lengths according to requirements. As seen at Figure 3, the connection-effecting cams 65 are placed one behind another upon the control block so as to be in position to depress the associated slides 53 which also stand one behind another. While the pin-bars 34 are lengthened rearwardly, as illustrated at Figures 3 and 5, the invention is not limited to the use of extended bars nor to the specific arrangement of jack trains and connection-effecting trains and control blocks.

At Figure 5 it will be seen that the first denominational jack train includes the rear-most rock-shaft 44 whose arms drive the left-hand pin-bars 34, these being the bars of highest denomination. The next jack train to be operated by the carriage as it proceeds from right to left includes the next forward rock-shaft which operates the pin-bars of the next to the highest denomination and so on, the last jack train including the front rock-shaft which operates the denominational pin-bars of lowest denomination. Thus the use of interposed transposition mechanism in the jack trains is rendered unnecessary; and so far as this feature of the invention is concerned, it is noted that it is applicable to machines in which a separate set of jacks is provided for each register, inasmuch as the use of the rock-shafts permits the above-explained simplicity of construction and operation whether or not the rock-shafts for one register are extended to operate the pin-bars or one or more additional registers.

It will be understood, of course, that the invention is not limited in its application to machines having three registers, and that additional registers may be employed by increasing the number of cams on the control blocks and providing suitable connecting mechanism between the additional cams and the pin-bars of the registers which they are to control.

Variations may be used within the scope of the invention, and portions of the improvements may be used without others.

Having thus described my invention, I claim:

1. In a typewriting and computing machine, in combination, a carriage, a set of digit keys, a plurality of registers, index pin-bars for said registers adapted to be set by operation of the digit keys but normally maintained away from position to be set, a series of shafts, arms on each shaft for moving the pin-bars of a single denomination in all of the registers to operative positions simultaneously, and means controlled by the carriage for operating the shafts in succession.

2. In a typewriting and computing machine, in combination, a set of digit keys, a plurality of registers, index pin-bars for

said registers adapted to be set by operation of the digit keys but normally maintained away from position to be set, and common denomination-selecting means including a set of members operable in succession and effective simultaneously in the several registers for moving the pin-bars of each register.

3. In a typewriting and computing machine, in combination, a carriage, a plurality of registers, index pin-bars and pin-setting means normally out of co-operative relation, a series of denominational rock-shafts each operable to move the pin-bars of a single denomination for all of the registers to position their index pins in co-operative relation to the pin-setting means, a rod connected to each rock-shaft, a jack for operating each rod, and a denomination-selector mounted on the carriage for operating the jacks in succession.

4. In a typewriting and computing machine, in combination, a carriage, a series of registers, index pin-bars and pin-setting means normally out of co-operative relation, and denomination-selecting mechanism effective in all of the registers simultaneously to move the pin-bars of each register successively into co-operative relation with their setting means and comprising a selector on the carriage, a set of jacks, a rod operated by each jack, a transverse rock-shaft operated by each rod, and pin-bar-setting arms fixed to each rock-shaft.

5. In a typewriting and computing machine, in combination, a plurality of registers, a set of index pin-bars for each register, a denomination-selector and a series of denominational trains common to the registers for moving their pin-bars to positions to have their pins set, each denominational train including a transverse rock-shaft, an upwardly-extending rod and a jack, the shafts being arranged one behind the other, and the rods and jacks each being arranged side by side, the rearmost shaft and the jack and rod at the extreme right being operatively connected and included in the train of highest denomination, the corresponding elements of the other trains being similarly connected and arranged in denominational order.

6. In a computing machine, in combination, a plurality of registers, a set of index pin-bars for each register, and mechanism for moving the pin-bars into positions to have their pins set comprising a series of rock-shafts, each shaft having an arm for moving it, and a plurality of arms each adapted to engage directly with an index pin-bar in one of the registers to move it.

7. In a computing machine, in combination, a register, index pin-setting means and a set of index pin-bars arranged in denominational order with the bar of lowest denomination at the right, a series of trans-

verse denominational rock-shafts arranged in denominational order with the rock-shaft of lowest denomination at the front, each of the index pin-bars having a pin at its rear end overlying the rock-shaft of appropriate denomination, a series of denominational jacks arranged in denominational order with the jack of lowest denomination at the left, and a rod actuated by each jack and connected to the rock-shaft of appropriate denomination.

8. In a computing machine, in combination, a series of registers, index pin-bars for each, a single set of denomination-selecting mechanism common to the registers, comprising a series of shafts extending transversely of the machine, and means operated by said shafts for moving the pin-bars of all the registers.

9. In a typewriting and computing machine, in combination, a carriage, a set of digit keys, a plurality of registers, index pin-bars adapted to be set by operation of the digit keys but normally maintained away from position to be set, means for moving to operative position pin-bars for all of the registers simultaneously, and mechanism controlled by the carriage for normally maintaining the pin-bars out of position to be engaged by the moving means.

10. In a computing machine, in combination, a plurality of registers, index pin-bars, and denomination-selecting mechanism, including a set of members operable in succession, common to the registers for directly driving the index pin-bars thereof, individually or concurrently.

11. In a computing machine, in combination, a plurality of registers, index pin-bars, denomination-selecting mechanism common to the different registers for moving the pin-bars, and means for normally maintaining the pin-bars above the paths of movement of the selecting mechanism and movable to permit the selecting mechanism to move the pin-bars in the different registers simultaneously.

12. In a computing machine, in combination, a plurality of registers, index pin-bars, denomination-selecting mechanism arranged to move pin-bars in all of the registers simultaneously, and means controlling the positions of the pin-bars for normally preventing movement of the pin-bars by the operation of the selecting mechanism.

13. In a computing machine, in combination, a plurality of registers, a series of index pin-bars for each register, said pin-bars having their pins normally out of position to enable them to be set, means for moving pin-bars of the same denomination into position to be set simultaneously, and means for upholding the pin-bars in part of the registers to prevent their being moved.

14. In a computing machine, in combina-

tion, a plurality of registers, a series of index pin-bars for each register, said pin-bars having their pins normally out of position to enable them to be set, denomination-selecting means for engaging and moving the pin-bars into position to be set, and separate means for moving the pin-bars of the registers into and out of positions to be engaged and moved by the denomination-selecting means.

15. In a computing machine, in combination, a series of registers, index pin-bars, denomination-selecting mechanism consisting of a set of jacks, rods and rock-shafts common to the registers, a series of arms on each rock-shaft, one for each register, having fixed paths of movement for engaging and moving the index pin-bars of the same denomination in the different registers, and a separate mechanism for maintaining the pin-bars of each register out of the paths of movement of the rock-shaft arms and individually operable to lower them into said paths.

16. In a computing machine, in combination, a series of registers, index pin-bars and means for normally maintaining the registers in inoperative condition, comprising three levers coaxially mounted, a yoke surrounding the pin-bars in each register, connections between each yoke and one of the levers, and a slide for operating each lever, said slides being arranged in alignment one behind the other.

17. In a typewriting and computing machine, in combination, a traveling carriage, a series of registers, a set of computing elements for each register arranged in denominational order descending from left to right of the machine, denomination-selecting mechanism for said computing elements, said denomination-selecting mechanism including a set of individual devices arranged in denominational order descending from right to left of the machine, and a set of transposing rock-shafts common to the several registers and operable by said devices, said devices being arranged to be operated from the traveling carriage, and controlling means arranged to cause all of the registers to be effective in one computing zone and a part of the registers to be effective in another computing zone.

18. In a computing machine, in combination, a series of registers, index pin-bars, denomination-selecting mechanism for moving the pin-bars of any selected register or registers at one time, and mechanism controlling the pin-bars of different registers separately to move them into and out of operative relation to the denomination-selecting mechanism.

19. In a typewriting and computing machine, in combination, a plurality of registers, register-selecting mechanism, control

blocks having cams thereon for controlling the selection of the registers in the computing zones, and independent mechanisms connecting the control blocks and the registers adapted to render any desired register or combination of registers operative in any zone according to the cams on the control block of that zone, regardless of the register selection in any other zone.

10 20. In a typewriting and computing machine, in combination, a carriage, a plurality of registers, index pin-bars, a plurality of rock-shafts for moving the pin-bars, and mechanism independently controlled from the carriage for determining the operative condition of each register.

15 21. In a typewriting and computing machine, in combination, a carriage, a plurality of registers, sets of computing elements therefor, controlling means acting on the computing elements for normally maintaining them in inoperative condition, and means for temporarily disabling said controlling means, to render the computing elements operative, comprising a block mounted on the carriage, a cam on the block, and a denomination-selecting tappet on said block for said computing elements.

20 22. In a typewriting and computing machine, in combination, a carriage, a plurality of registers, separate means normally maintaining the registers in inoperative condition, said means for each register comprising a slide and a spring upholding said slide, a cam pivotally mounted on the upper end of each slide, and means mounted on the carriage for engaging the cams and thrusting them and their slides bodily downward.

25 23. In a typewriting and computing machine, in combination, a carriage, a register, a slide normally drawn into position to render the register inoperative, a block on the carriage for thrusting the slide bodily downward to render the register operative, a cam pivoted on the upper end of the slide to cooperate with the block, a pin on the slide for limiting the rotation of the cam in one direction, and a spring normally forcing the cam to its limit of movement.

30 24. In a typewriting and computing machine, in combination, a register, index pin-bars and mechanism controlling the positions of the pin-bars and thereby controlling the operative condition of the register, said controlling mechanism comprising a yoke for raising and lowering all of the index pin-bars concurrently.

35 25. In a combined typewriting and computing machine, the combination of a carriage feeding from right to left, a plurality of registers, a set of indexing devices for each register and arranged in denominational order descending from left to right of the machine, a single set of denomination-selecting connections common to all of the

registers, said denomination-selecting connections including jacks arranged in denominational order descending from right to left of the machine, a set of transposing rock-shafts extending crosswise of all of the indexing devices, and a set of connections from the jacks to said rock-shafts, and a plurality of sets of connections from the rock shafts to the indexing devices of the several registers.

70 26. For use in a typewriting and computing machine, a control block adapted to be readily inserted and removed from the machine having, in combination, means for positioning the block in various locations laterally of the machine, a plurality of register-selecting cams on its lower face, and a denomination-selector on the upper face of the block.

75 27. In a computing machine, in combination, a register, index pin-bars, a rock-shaft corresponding to each of the bars, elements fixed to each bar and rock-shaft, respectively, for direct engagement with each other, whereby movements of the rock-shafts are effective to move the pin-bars, and means for preventing movement of the pin-bars by the rock-shafts.

80 28. In a typewriting and computing machine, in combination, a register including digit bars, index pin-bars, the latter normally positioned with their pins out of alignment with the digit bars, denomination-selecting means for thrusting the pin-bars forward, and means for raising the pin-bars 100 out of the paths of movement of the denomination-selecting means.

85 29. In a computing machine, in combination, a register, a series of index pin-bars having their pins normally out of positions to enable them to be set, means for moving the pin-bars selectively into pin-setting positions, and a yoke normally upholding the pin-bars to prevent their being moved to pin-setting positions.

90 105 30. In a computing machine, in combination, a register, a series of index pin-bars having their pins normally out of positions to enable them to be set, denomination-selecting mechanism to move the pin-bars selectively to setting positions, means for normally upholding the pin-bars out of the paths of movement of the denomination-selecting mechanism, and means for depressing the upholding means to lower the pin-bars.

110 125 31. In a computing machine, in combination, a denomination-selector, a set of jacks operated thereby, a rod operated by each jack, a rock-shaft connected to each rod to be rocked by it, an arm on each rock-shaft having a fixed path of movement, a series of denomination pin-bars, each adapted to be moved to operative position by engagement with a rock-shaft arm, and means nor- 120 130

5 mally holding the pin-bars beyond the paths traversed by the rock-shaft arms.

32. In a computing machine, in combination, a register, a series of index pin-bars, mechanism normally yieldingly upholding the pin-bars to render the register inoperative, and means for positively thrusting the upholding means downward to lower the pin-bars and thereby to render the register operative.

10 33. In a computing machine, in combination, a register, index pin-bars, a yoke surrounding the pin-bars, a spring yieldingly upholding the yoke to maintain the register in operative condition, and means for automatically depressing the yoke to render the register operative at a predetermined stage in the operation of the machine.

20 34. In a typewriting and computing machine, in combination, a carriage, a register, index pin-bars, a yoke surrounding the pin-bars to raise and lower them, denomination-selecting mechanism effective to move the pin-bars when the latter are in their lowered positions, and means movable with the carriage for controlling the movements of the yoke.

30 35. In a typewriting and computing machine, in combination, a carriage, a register, a slide normally maintained in an elevated position to render the register inoperative, a cam on said slide, and means mounted on the carriage for engaging said cam and thrusting the slide downward to render the register operative.

40 36. In a typewriting and computing machine, in combination, a carriage, a denomination-selector on the carriage, a register, a series of denominational pin-bars, and denomination-selecting mechanism operative by the selector, consisting of a series of denominational trains for operating the several pin-bars, each train consisting only of a jack, a rod and a rock-shaft connected to the rod and having an arm for moving the denominational pin-bars.

50 37. In a combined typewriting and computing machine, a traveling carriage, a register, denomination-selecting mechanism comprising a series of transverse rock-shafts arranged one behind another, a series of thrust rods connected at their lower ends to the rock shafts, a series of denominational jacks to engage the upper ends of the thrust rods and depress them seriatim, and a guide for the thrust rods adjacent their upper ends to converge their upper ends and cause them to lie in a straight line in the direction of carriage travel for engagement by the jacks.

60 38. In a combined typewriting and computing machine, a traveling carriage, computing mechanism comprising denominational pin-bars, denomination-selecting members arranged for operation seriatim by the travel of the carriage, and mechanism op-

erated by a single denomination-selecting member to move a plurality of pin-bars to pin-setting position.

70 39. In a computing machine, the combination with numeral-keys and types, of a plurality of registers, normally-inoperative key-controlled indexing mechanisms for said registers, including trains of denomination-selecting mechanism for rendering said indexing mechanism effective, each train 75 including a denomination-selecting rock-shaft extending transversely of the machine, and members fixed to the rock-shaft for moving indexing members of the same denomination to effective positions in all of the 80 registers, and means for operating the registers according to the setting of the indexing mechanisms.

85 40. In a combined typewriting and computing machine, the combination of a carriage, key-controlled indexing means including a set of denomination-selecting devices arranged substantially in the middle of the machine and actuatable by said carriage, a register located to one side of the machine, 90 said register having a set of computing elements, and a set of denomination-transposing rock-shafts connecting the set of denomination-selecting devices with the computing elements, said rock-shafts at one set of their 95 ends engaging with said denomination-selecting devices, and all extending away therefrom, in the same direction, and at the other set of their ends engaging with said computing elements at points remote from said 100 set of denomination-selecting devices, and means for operating the registers according to the setting of the indexing devices.

105 41. In a typewriting and computing machine, in combination, a series of stationary registers, a set of computing elements for each register normally maintained in inoperative condition, independent controlling means for each set of computing elements to render it operative, said controlling means 110 for the several sets of computing elements being arranged for separate or concurrent operation, and denomination-selecting mechanism arranged to operate upon the computing elements while they are maintained in 115 an operative condition by the controlling means.

120 42. In a typewriting and computing machine, in combination, a carriage, a series of stationary registers, a set of computing bars normally maintained in inoperative condition for each register, controlling means for each set of computing bars, each set of computing bars arranged for operation separately from the others or concurrently therewith, means mounted on the carriage for actuating the controlling means, and denomination-selecting mechanism arranged 125 to operate upon all of the computing bars 130

maintained in an operative condition by the controlling means.

43. In a combined typewriting and computing machine, a traveling carriage, a series of registers, a set of computing bars for each register, denomination-selecting mechanism including a single set of transposing rock-shafts, and means controlling the operative condition of the registers individually, including a series of rods arranged side by side, means on the carriage for individually engaging and depressing the rods, and common guiding means for the rods to hold all of them in position to be engaged by their respective moving means, said controlling means including connections from said rods to said computing bars by which the actuation of one of said rods brings the associated set of computing bars into effective relation with the rock-shafts.

44. In a combined typewriting and computing machine, the combination of a carriage, setting devices, a plurality of registers, a set of indexing devices for each register, a single set of denomination-selecting connections for said indexing devices, and including a set of transposing rock-shafts extending crosswise of the indexing devices, a single set of carriage-operated connections extending from said rock-shafts, and a plurality of sets of arms on said rock-shafts to engage the sets of indexing devices, the direction of the set of carriage-operated connections being opposite to the direction of the sets of vertically-disposed arms, so that said connections operate the indexing devices in the order from left to right of the machine, and register-selecting mechanism including individual devices, one associated with each set of indexing devices, to bring the associated set of indexing devices into co-operative relation with the corresponding set of arms on the rock-shafts.

45. In a combined typewriting and computing machine, the combination of a carriage, setting devices, a plurality of registers, each having a set of indexing devices and a single set of denomination-selecting connections for said indexing devices, including a set of transposing rock-shafts located toward the rear and beneath the ends of the indexing devices, a single set of carriage-operated connections extending from said rock-shafts and a set of arms, one on each rock-shaft, to engage the indexing devices, said set of carriage-operated connections and said set of arms being crossed with respect to each other, so that the connections when operated by the carriage operate the indexing devices to move them individually into co-operative relation with the setting devices, and register-selecting mechanism including devices, one associated with each set of indexing devices, to lower the rear ends

of the indexing devices into co-operative relation with the upwardly-extending arms.

46. In a combined typewriting and computing machine, the combination of a plurality of registers, sets of indexable computing elements, a carriage, denomination-selecting mechanism including a set of transposing rock-shafts actuatable by said carriage, a plurality of sets of devices on said rock-shafts, one set for each register, said computing elements being normally out of range of the actuatable devices, and register-selecting devices including means to render the computing elements effective with the actuatable devices.

47. In a combined typewriting and computing machine, the combination of a plurality of registers, sets of indexable computing elements, a carriage, denomination-selecting devices, a set of transposing rock-shafts actuatable by said carriage, a plurality of sets of devices on said rock-shafts, one set for each register, register-selecting devices to render the computing elements effective with the actuatable devices, and means on the carriage to actuate said register-selecting devices.

48. In a typewriting and computing machine, in combination, a plurality of registers, key-controlled indexing devices including pin-bars, and also including denomination-selecting mechanism common to the registers consisting of a series of denomination-selecting trains, each train comprising a rock-shaft extending transversely of the machine throughout the entire width of the machine frame, for connection with a plurality of registers, and means for operating the registers according to the setting of the indexing devices.

49. In a combined typewriting and computing machine, the combination of a carriage, key-controlled indexing means including setting devices, a plurality of registers, denomination-selecting mechanism being comprised in said indexing means and including a series of denomination-transposing rock-shafts and a single set of carriage-operated denomination-controlling connections extending from said rock-shafts, a plurality of sets of denomination-controlling connections from the rock-shafts to the indexing devices of the several registers, register-selecting devices to render the registers effective, the single set of carriage-operated denominational connections being effective to operate the indexing devices of the effective registers, and means for operating the registers according to the setting of the indexing devices.

BURNHAM C. STICKNEY.
